(57) **CLAIM**

The ornamental design of a carrier rack for elastic tie-down straps, as shown and described.

DESCRIPTION

FIG. 1 is a perspective view of a carrier rack for elastic tie-down straps showing my new design, with a middle portion broken away to disclose indefinite width;

FIG. 2 is a side view thereof with a middle portion broken away to disclose indefinite width, the opposite side view being the same;

FIG. 3 is an end view thereof, the opposite end view being the same; and,

FIG. 4 is a top view thereof with a middle portion broken away to disclose indefinite width, the bottom view being the same.

The elastic straps shown in phantom in FIG. 1 are for illustrative purposes only and form no part of the claimed design.
